REVOLVER HOLSTER

Clifford A. Ray, Williams, Ariz.

Application March 16, 1936, Serial No. 69,146

3 Claims. (Cl. 224—2)

This invention relates generally to revolver holsters but more particularly to such holsters of the type wherein a safety latch is provided to prevent the accidental dislodgment, removal or withdrawal of the revolver from the holster or its discharge while retained therein.

An object of the invention is to provide a simple and compact holster provided with a latch mechanism of simple and rugged construction, whereby the revolver will be retained within the holster until it is intentionally withdrawn; another object is to provide a retaining latch of a design such that withdrawal may be easily and quickly had by the user of the revolver by a natural and simple movement of the arm and hand; still another object is to provide such a retaining mechanism that the withdrawal is made decidedly awkward or practically impossible by any one other than the bearer of the arm. Other objects will appear hereinafter.

I attain these objects by the construction and devices illustrated in the accompanying drawing, in which—

Fig. 1 is a vertical elevation of the holster with a revolver in place therein, with the front portion of the holster sectioned off to show the position of the revolver and the latching mechanism; Fig. 2 is an end elevational view of the holster alone as would be viewed from the right hand of Fig. 1; Fig. 3 is a somewhat enlarged view of the thumb guard portion of the latching mechanism as would be viewed from the left hand side in Fig. 1; Fig. 4 is an enlarged fragmentary section, taken on lines 4—4, Fig. 2.

Similar numerals refer to similar parts of all views.

The holster body as designated by numeral 2, is of somewhat conventional design and is shaped and fitted to fit the particular type of revolver, designated by numeral 3, that it is intended to carry.

While the illustration herewith is for a right handed holster, it is to be understood that this design will work equally well for either left or right handed holsters.

The latching mechanism consists of a flat steel spring 6 attached to the top or forward edge of the holster at a position about midway from the muzzle end and the top edge. This attachment 50 may be effected by a bolt or rivet 1 and an inwardly bent tongue portion of the spring 8. At the upper end of this spring the latch, designated by numeral 4, is attached so that there is a normal tension pressing its upper end toward 55 the body of the holster, so that latch is normally

forced inwardly and the vertical portion held tightly against the forward portion of the holster body. In the preferred form, as shown in Fig. 4, the spring is bowed slightly so as to increase this normal tension. The latch 4 is formed of metal having an angular bend to form a structure similar to an inverted L. The vertical portion is attached to the upper end of spring 6 by rivets 9, and the horizontal portion extends inwardly toward the body of the holster and has an arcuate bend dependent on a radius struck off from the main point of flexure of spring 6. This is designated in Fig. 4 by the dotted lines 27. This horizontal portion of the latch forms a stop bar 28, which is provided at its innermost edge with a raised ridge forming a dog 16. Above this dog is a thumb guard 10, having a semi-conical shape, and an arcuate section. This extends upwardly and to the left, following, angularly, the general contour of the handle 11 of revolver 3 and ends approximately just back of the upper portion of this handle. The upper arched edge 12 of the thumb guard 10 is flared and rounded and provided with beading to facilitate entrance into the tunnel 14 formed by its concaved lower face.

To steady and prevent lateral movement of the latch, the horizontal portion extends through a slot 15 in the upper part of the forward rounded edge of the holster body.

While the outer side of the holster is shown removed in Fig. 1, the outline of its upper edge is indicated by dotted lines 29 and, as thus indicated, it will be understood that there is a drop or cut-away portion in this side to expose the trigger 26 of revolver 3. Thus the general structure of the holster permits at all times an easy grasp of the handle 11, and free access to the trigger within trigger guard 20.

When the arm is fully inserted into the holster, the horizontal portion of the latch forming retainer bar 28 extends over hammer 5 of the revolver 3, and is retained in this position by the normal tension of spring 6. Dislodgment of the hammer from this position is prevented by dog 16, and it is best practice to fit the arm within the holster so that there is a slight downward resilient pressure on the hammer by retainer bar 28. Thus the arm is held in place by the spring pressure which is exerted principally downwardly, although dislodgment of the arm is also maintained by the retention of the upper edge of thumb grip 17 of the hammer, by dog 16. It is thus possible to maintain a slight downward pressure of the retainer bar on the portion of the hammer 17 by tension maintained by a mid-

flexure of spring 6. Since the revolver 3 is held wedged within the holster in such a manner that the top portion of the frame 18 is forced against the inside of the forward edge 19 of the holster 5 and the trigger guard 20 is wedged against the rear edge 21 of the holster, there is no appreciable movement of the arm within the holster between these two edges. Therefore, the arm 3 is held securely in place within the holster by the 10 resistance to upward movement exerted by retainer bar 28 on the thumb grip portion 11 of hammer 5.

When it is desired to withdraw the arm, the natural movement of the bearer is to insert his 15 thumb, designated by numeral 22 of the dotted outline of the hand 23, within the tunnel 14, being the concave portion of thumb guard 10 following the upper contours of the revolver handle 11, and the index finger 24 is naturally extended toward the trigger guard 20. As the hand of the operator is further moved in the act of gripping the arm, the thumb guard is naturally and necessarily forced upward and to the right, taking the position indicated by the dotted outline 25, at 20 which position it is held only so long as the thumb is inserted, since this position is maintained against the normal tension of spring 6. At the same time the index finger 24 has immediate access to trigger 26. Moving the thumb guard 10 and latch to the position indicated by the outline 25 releases the revolver and it may be quickly and naturally withdrawn from the holster, being held by the third, fourth and fifth fingers on handle 11, while the index finger is already in position 25 on the trigger. This permits the arm to be not only quickly grasped and withdrawn, but also withdrawn ready for firing. Since the index finger has free access to the trigger as soon as the handle is grasped in the act of withdrawing, it 30 is not necessary to shift the position of the hand after the arm is withdrawn from the holster, but the arm may be fired at once.

When the arm is to be re-inserted into the holster it will be obvious that, after the insertion 45 of the muzzle, the hammer easily follows the tunnel of the thumb guard forward and downward, until the thumb portion of the hammer 17 passes the edge 16 of the latch wherein it is again locked in position.

50 In the form herewith illustrated, the latch 4 operates on the back tip or thumb plate 17 of the hammer 5 of revolver 3. It is to be understood, however, that in constructing holsters and latches for types of revolvers or other arms not having 55 a hammer, the latch will operate on any similar convenient projection on, or attached to, the arm.

From the foregoing construction it will be apparent to those familiar with the art, that any one save the bearer of the arm will have difficulty in holding the latch in released position and withdrawing the arm at the same time. Any attempt to grasp the handle of the arm by any other person would, necessarily, force the thumb guard 10 more tightly into closed position. On the other hand, the natural movement of the bearer of the arm, as made in gripping the handle 11, is to place his thumb in position to release the latch.

70 While I have herewith illustrated the preferred form of my invention only, it will be easily understood by those familiar with the art that the structure herewith shown is adapted to changes and modifications but that these would, nevertheless, still remain within the spirit and general

principles of my invention. Therefore, I wish to be limited only by the following claims.

I claim:

1. A revolver holster comprising, in combination, a holster body having a rounded forward edge, a comparatively narrow rearward edge and interiorly shaped to substantially conform to the contour of the muzzle, cylinder and trigger mechanism of the revolver to be received therein, a latching mechanism adapted to yieldably retain 5 said revolver within said holster body comprising a vertically extending spring attached to the outside of the forward edge of said holster body, said spring being affixed at its lower end and having its upper end free to move, a latching bar attached to the upper free end of said spring and extending substantially horizontally rearwardly through a slot in the forward edge of said holster body and thence to a position above the upper 10 edge of the thumb guard of the hammer portion of a revolver carried in said holster body, a downwardly extending dog attached to the rear end of said latching bar and a latch release consisting of an arched semi-conical segment affixed at its smaller end to the rear end of said latching 15 bar and extending thence rearwardly at an angle substantially conformable to the upper edge of the handle of said revolver carried in said holster, said thumb guard being positioned with its concave face downward forming a tunnel-like guide 20 way extending toward the hammer of said revolver, said upwardly extending spring being normally flexed against the outer face of the forward portion of said holster body whereby a forward movement of said thumb guard acts against the 25 normal tension of said spring and forces said latching bar forward and outward through said slot in the forward edge of said holster body whereby it is removed from a position above the 30 hammer on said revolver.

2. A revolver holster comprising, in combination, a holster body shaped to substantially conform to the contour of the muzzle, cylinder and trigger guard of the arm to be carried therein, whereby said arm may be restrained therein 45 against forward and rearward movement, and having the outer sheath portion cut away to permit access to the trigger of the arm, together with a latching mechanism, including a vertically positioned spring attached at its lower end to the 50 outside of the forward portion of the holster body, being free to flex independent of the holster body, a substantially horizontal latch bar at its upper end extending over and cooperating with the outermost portion of the hammer of the arm 55 within said holster body to form means of retention of the arm when said spring is in normal position, and unlatching means, including a conical concavo-convex hood attached to the rear end of said latch bar and extending over the 60 handle portion of the arm within said holster to provide a tunnel like recess intermediate said plate and the upper portion of said arm to receive the thumb of the bearer of the arm whereby said latch bar may be forced forward against the tension of said vertical spring to effect release of the arm from said holster body.

3. A revolver holster comprising, in combination, a holster body adapted to receive the arm and yieldably retain same against forward and rearward play, a latching mechanism to retain 70 said arm within said holster body comprising a latch bar, operative over the projecting portion of the hammer of the arm retained within said holster body, supported on a vertically extending 75

spring attached at its lower end to said holster body, flexing independently of the holster body, and normally holding said latch bar rearward and over the hammer of said arm within said holster, and latch releasing mechanism including a conical hood attached to said latch bar, ex-

tending over and forming a tunnel-like recess over the handle portion of the arm, to receive the thumb of the bearer of the arm whereby a forward movement of said latch bar is effected against the tension of said supporting spring. 5
